UNITED STATES PATENT OFFICE.

JOHN S. ROWELL, OF BEAVER DAM, WISCONSIN.

PAVEMENT.

SPECIFICATION forming part of Letters Patent No. 533,498, dated February 5, 1895.

Application filed October 29, 1894. Serial No. 527,280. (No model.)

To all whom it may concern:

Be it known that I, JOHN S. ROWELL, a citizen of the United States, and a resident of Beaver Dam, in the county of Dodge and State of Wisconsin, have invented certain new and useful Improvements in Pavements; and I do hereby declare that the following is a full, clear, and exact description thereof.

My invention has for its object to provide a strong, durable and economical pavement that will not spread, warp, or crack; and it consists of a metallic skeleton frame combined with a plastic filling laid upon a suitable foundation the same being hereinafter more fully described with reference to the accompanying drawings and subsequently claimed.

In the drawings: Figure 1 represents a plan view of a partly finished section of pavement constructed according to my invention; Fig. 2, a vertical transverse section of the same taken on line 2—2 of the preceding figure; Fig. 3, a similar view of a portion of the pavement on a larger scale than that of the previous figures; Fig. 4, a perspective view of a portion of one of the transverse stays employed in the preferred form of skeleton frame that constitutes part of my improved pavement; Fig. 5, a similar view of one of the inner longitudinal bars employed in said preferred form of skeleton frame, and Fig. 6, a detail elevation partly in section illustrating a union of the aforesaid stay and bar.

Referring by letter to the drawings, A represents parallel side-bars made from any suitable metal in such widths and thickness as may be most desirable, but under ordinary circumstances bars of one and one-quarter inches wide by one-quarter of an inch thick will answer. In practice the side-bars are stayed apart any desirable distance by suitable metallic material, such as wire netting, rods or band-iron strips, to thereby form a skeleton-frame primarily open at the top and bottom, this frame being laid upon a cinder, clay or other suitable foundation and subsequently filled with a plastic material to complete the pavement. The metal skeleton-frame is made in sections of any convenient length, say twelve feet, and these sections are united by any suitable means as the laying of the pavement progresses.

The end sections of the metal skeleton-frame have the outer extremities of the side-bars A rigidly connected to a transverse stay 55 B, and in practice the width and thickness of the latter bar are preferably the same as like dimensions of said side-bars.

At suitable intervals in the length of the skeleton-frame I provide anchors C that may 60 be of any length in a vertical direction, said anchors being preferably right-angle strips of band-iron riveted to the side-bars of said frame inside the latter. In practice I have found it sufficient to make the anchors of 65 band-iron one-quarter of an inch thick, three inches wide and six inches deep, the flukes or horizontal portions of said anchors having two inches, more or less, extension from the shanks.

When setting the frame, I prefer to have the side-bars in one section thereof butt-join those of a succeeding section and then unite said sections by means of metal splice-plates D riveted to said butt-joined side-bars.

That form of skeleton-frame herein shown embodies longitudinal bars E of a width equal to that of the side-bars between which they are in parallel arrangement at regular intervals, and I also employ a series of transverse stays F that have the same width and interlock with the intermediate bars at such intervals as may be determined whereby I form rectangular compartments in said frame. The bars E and stays F may be less thick 85 than the side-bars of the frame and I have found that one-eighth of an inch is a sufficient thickness.

The bars E in a section of the frame are preferably longer than the side bars A of the 90 same section and are lap-joined and riveted to the meeting bars of an adjacent section or sections, the interlocking stays F being riveted or otherwise rigidly secured to said side bars. In a terminal section of the frame the 95 bars E are riveted or otherwise rigidly secured to one of the stays B above specified.

In order to interlock the bars E and stays F both are kerfed at the proper intervals one-half their depth, and it is apparent that a kerf in one will be engaged by the other. I also find it preferable to notch the lower edges of the bars E in line with each kerf and swage kerf-corners of a stay F therein as shown in

Fig. 6, thus locking said bars against displacement when the frame-sections are being handled.

A frame of the above description having been positioned on a suitable foundation the spaces therein are filled with any suitable plastic material to complete the pavement, and I prefer a mixture of cement, sand and water, or this mixture as a top dressing for another mixture of gravel, cement and water, both being shown in Fig. 3.

The filling above described is tamped tight in each compartment of the frame and struck off to obtain a nice finish. The tamping insures of soft spots in the foundation being packed hard, the filling being supplied as the work proceeds and tamped until it ceases to sink, and the material struck off from a compartment is utilized in another adjacent compartment.

Owing to the tamping operation I obtain the greatest possible cohesion of the filling material in the frame compartments, and I have found by experiment that there is no shrink of said material from the boundaries of said compartments, and that the finished pavement will neither spread, warp nor crack under the varying conditions to which pavements are subjected. I have also found by experiment that a comparatively small quantity of cement is necessary in the filling material and consequently this effects a saving

in the cost of the pavement, these results being due to the fact that each section of the filling is braced on all sides by the metal frame-work of said pavement, and it is possible to make the compartments of the frame in various shapes according to the disposition of the metal work intermediate of the side-bars.

Having thus described my invention, what I claim as new, and desire to secure by Letters Patent, is—

1. A pavement frame comprising metal side bars and interlocking metal-work intermediate of the bars, certain members of the metal-work being provided with notches and kerf-corners of other members of said metal-work swaged into the notches.

2. A pavement-frame resulting from metal side-bars joined by metal stays and having anchors depending from said side-bars.

3. A pavement-frame resulting from metal side-bars and an intermediate net-work of like material joined thereto, together with anchors depending from said side bars.

In testimony that I claim the foregoing I have hereunto set my hand, at Beaver Dam, in the county of Dodge and State of Wisconsin, in the presence of two witnesses.

JOHN S. ROWELL.

Witnesses: W. H. STACY, B. S. BARBER.
